ELECTRIC SWITCH

James M. de Montmollin and Thomas E. Curtis,
Hampton, Ga., assignors to Southern States
Equipment Corporation, a corporation of
Georgia

Application May 31, 1947, Serial No. 751,568

8 Claims. (CL 200—48)

1

This patent relates to high voltage electric switches of the type in which two contact-making terminals, relatively movable, are first brought into engagement with one another and then the pressures between the terminals are greatly increased by continued relative movement between these said members.

One purpose is to provide a switch of this type in which a relatively slight movement of the terminals develops the desired minimum high pressure, another purpose is to limit this pressure to a predetermined maximum while permitting considerable variations of members and movement. Another purpose is to provide a compact, and durable pre-stressed spring which will maintain the desired high pressures over a considerable range of travel, and which can be readily adjusted to obtain proper coordination of the pressure members for each individual switch unit. Another purpose is to provide contact members which all have high conductivity. Other purposes will be evident from the specification and claims.

In the drawings, Figs. 1 and 2 show in small scale two views of a single pole switch unit of one design embodying this invention; Fig. 3 is a larger scale view of the terminals not fully closed; Fig. 4 is plan view of terminals when fully closed; Fig. 5 is a side view of terminals when closed; and Fig. 6 is a cross section view on section 6—6.

A base 1 carries two bearings which support the two rotatable insulator units 2, 3, and these are interconnected by the rod 4. The crank 5 is the means for rotating both insulator units simultaneously in opposite directions. Line connections 6, 7 are pivotally secured to units 2, 3, respectively; and arms 8, 9 are solidly secured to insulator units 2, 3 respectively.

Arm 8 carries terminal 10, which is preferably a single conducting forked member secured to arm 8 by bolt 11. The tips of the tines, 12, 13, are flared and they act as guides, the ribs 15, 15 and the webs 16, 16 stiffen the fork, and the two sides of the fork have contact surfaces 17, 17 which are substantially parallel and these sides may be silvered or otherwise finished as desired.

Arm 9 carries a terminal assembly 18 made of two similar members which are clamped to arm 9 by bolts and nuts 19—19. The flat bar portions 20, 20 have enough flexibility to allow the small area, high pressure contacts 21, 21 to be expanded or contracted without producing improper strains. The tapered tips 21', 21' act as guides as the terminals are becoming engaged. The webs 22, 22 and 23, 23 together with the

2

covers 24 and 25 enclose the space where the spring 26 is housed. Bolt 27 and nuts 28, 29 are used to compress spring 26 to exert the desired minimum high pressure against the two members of 18. One or more washers 30, may be inserted or removed as desired so that the contacts 21, 21 are properly spaced when spring 26 is compressed to give this desired tension.

The spacing between 21, 21 is such that the 10 assembled terminal 18 is readily inserted between surfaces 17, 17 when terminals 10, 18 are at an angle as shown in Fig. 3; and yet when arms 8, 9 have been brought into alignment as shown in Figs. 2 and 4, then the contacts 21, 21 have 15 been compressed slightly thereby removing all stress from bolt 27 and nuts 28, 29 so that the full stress of spring 26 is exerted in opposite directions to produce equal pressure between contacts 21, 21 and their respective surfaces 17, 17.

20 Operation is as follows:

Assume that the switch is open and the arms 8, 9 are in the positions shown by dotted lines in Fig. 2. The longitudinal axes of the two arms are in the same operating plane but they are at 25 angular positions to one another. Both tines of the fork 10 and the two contacts 21, 21 all move in this same operating plane and so a closing motion of crank 5 will bring the arms together until fork 10 and the terminal assembly 18 engage as shown in Fig. 3, with the two contacts 21, 21 in an angular position between the sides 17, 17. Further closing motion brings the longitudinal axes of the two arms 8, 9 substantially into alignment as shown in full lines in Fig. 2, 30 and the contact members come into the positions shown in Fig. 4.

The contacts 21, 21 have thereby been squeezed together by faces 17, 17 with a scraping action 40 which removes dirt and scale from all contact surfaces, and the heavy pressure from spring 26 ensures high conductivity contacts everywhere. A compression motion of a few hundredths of an inch is enough to transfer the pressure of spring 26 from bolt 27 to surfaces 17, 17. And a coil 45 spring such as 26, which is already compressed to exert a pressure of say 200 pounds, can be compressed another sixteenth of an inch or more without developing more than say 250 pounds of pressure. Thus, the spring 26 which is pre-stressed to give the minimum desired pressure, can readily be compressed as much more as may be required by irregularities of individual switch units, without developing such heavy pressures that the parts can be operated only with great 50 difficulty.

There is the same conductivity in all similar members, the current flow is thereby divided into two similar paths, and so the heating effect is low.

This invention can be used in a switch in which the two switch arms are of different lengths; either terminal with its supporting arm may be made as a single member instead of being an assembled structure; the switch arms may be mounted and operated in various ways, so long as they can be given the required movement relative to one another; the contacts 21, 21 may be disposed in a plane that is not necessarily normal to the length of arm 8; and other changes can be made by one familiar with the art without departing from the spirit and purposes of this invention.

We claim:

1. In an electric switch, two relatively movable conductor terminals pivotally mounted in spaced relationship and cooperable to swing into and out of engagement with one another one of said terminals being a rigid fork, the second terminal comprising two similar elongated conducting members clamped together at one end and with a pair of expansible and compressible high pressure contacts at their other end, a coil spring to bias the pair of contacts towards expansion and stop means to limit said expansion, integral parts of the said two elongated conducting members also forming a protective enclosure to house said coil spring.

2. In an electric switch, two spaced insulated supports, a terminal conductor in the form of a rigid fork movably supported by one of said supports, and movably supported on the other of said supports a second terminal comprising two spaced contacts biased apart from one another and with their separation limited by a stop, both tines of the said fork and the said two spaced contacts being swingable in the same operating plane with one another, together with operating means for positioning the said second terminal freely between the sides of said fork and thereafter for moving said second terminal and the said fork angularly with respect to one another to force said two spaced contacts more closely together.

3. In an electric switch, a conducting terminal in the form of a rigid fork, a second terminal comprising two spaced contacts and a spring biasing said contacts apart and a stop to limit the separation of said contacts, the normal width of said second terminal being greater than the space between the sides of said rigid fork, both tines of the fork and the said two spaced contacts all being swingable in the same operating plane with one another, together with means operative by one continuous motion to move said two contacts freely into the space between the sides of said fork and thereafter to move the said two contacts angularly with respect to said fork and thereby to force said two contacts more closely together.

4. In an electric switch, a pair of spaced insulators, a pair of switch arms each with a terminal on its swing end, said switch arms being supported by said insulators and being rotatable simultaneously about their respective axes to bring said terminals into mutual engagement, one of said arms carrying as its terminal a rigid fork, the other said arm carrying as its terminal a pair of spaced contact members and a spring biasing said contact members apart and a stop to limit the separation of the contact surfaces of said contact members, the normal spacing of said contact surfaces being so related to the transverse width

5 between the sides of said fork that said contacts enter freely into the space between the sides of said fork as the terminals begin their mutual engagement but by the continued rotation of said switch arms the said contact surfaces are forced more closely together by pressure against the sides of said fork.

10 6. In an electric switch, two swingably mounted conducting terminals cooperable to open or to close the switch, one of said terminals being a fork with a fixed space between the substantially parallel sides of the fork, the other of said terminals including two relatively movable contacts normally spaced to a width greater than the said fixed space between the sides of the fork, both 15 tines of the fork and the said two spaced contacts being swingable in the same operating plane with one another, together with means operative to swing the said two contacts freely and in a position angular to the longitudinal axis of the fork into the said space between the sides of the fork, and thereafter to move the said two contacts within the said fork into a position transverse to the longitudinal axis of the fork and thereby to 20 force the two contacts more closely together.

15 7. In an electric switch, a pair of cooperable switch arms mounted for rotation, respectively, about two spaced parallel axes, a rigid fork as a terminal on the swing end of one of said arms, 30 a terminal assembly on the swing end of the other said arm and engageable with said fork, the said terminal assembly including a pair of high pressure contacts which form a transverse compressible head with a normal width greater than the space between the two sides of said fork, both tines of the fork moving in the same operating plane as that in which the two arms swing, together with means operative to rotate simultaneously the two arms about their respective axes and thereby to position the compressible head freely in an angular position within the space between the sides of the said fork, and thereafter by continued rotation of the arms to bring the head into a position transverse to the longitudinal axis of the fork thereby to compress the said head.

40 8. In an electric switch, a pair of cooperable switch arms mounted for rotation, respectively, in the same operating plane, about two spaced parallel axes, a rigid fork as a terminal on the swing end of one of said arms, both tines of said fork being in the said operating plane, a terminal assembly on the swing end of the other said arm and engageable with said fork, the said terminal assembly including a pair of high pressure contacts which form a transverse compressible head with a normal width greater than the space between the two sides of said fork, together with means operative to rotate simultaneously the two arms about their respective axes and thereby to position the compressible head freely in an angular position within the space between the sides of the said fork, and thereafter by continued rotation of the arms to bring the longitudinal axes of the said two arms into alignment.

45 9. In an electric switch a pair of cooperable switch arms each rotatable about its own axis and both arms rotating in the same operating plane, each arm with a conducting terminal on its swing end cooperable with the other terminal to open or close the circuit, one of said terminals being a rigid fork which has both its tines in the said operating plane, the other said terminal including two relatively movable contacts which are both in said operating plane and which are

normally spaced to a width greater than the space between the sides of the fork but which are compressible towards each other, together with means operative to rotate at least one of said arms and thereby to position the said two contacts freely within the space between the sides of said fork and thereafter to rotate the two arms simultaneously to position the said two contacts transversely to the said fork and thereby to compress said two contacts more closely together.
